UNITED STATES PATENT OFFICE.

HENRY L. DOHERTY, OF NEW YORK, N. Y.

APPARATUS FOR REGULATING THE AIR-SUPPLY FOR GAS-PRODUCERS.

1,101,787.

Specification of Letters Patent. Patented June 30, 1914.

Application filed February 15, 1910. Serial No. 544,097.

To all whom it may concern:

Be it known that I, HENRY L. DOHERTY, a citizen of the United States, and a resident of New York city, in the county of New York and State of New York, have invented certain new and useful Improvements in Apparatus for Regulating the Air-Supply for Gas-Producers, of which the following is a specification.

10 My invention relates to apparatus for regulating the air supply for gas producers and, particularly, to gas producers burning bituminous coal.

The object of my invention is to furnish 15 in connection with such producers an apparatus which will provide for a uniform make of combustible gas in the producer and consequently for uniform conditions of combustion in the furnace in which the combustible gas is burned.

When gas coal is used in the producer, great irregularity is occasioned in the make of gas, due to the rapid distillation of gas from the coal, immediately after the latter 25 has been charged onto the bed of incandescent fuel in the producer. The result is that, for an appreciable time after charging, the make of gas in the producer is increased by the volume of gas distilled from 30 the coal. Unless the air supplied to the furnace is increased to correspond, the result is that a considerable quantity of combustible passes through the furnace unconsumed, to be later burned at the stack or to 35 pass into the air unburned, as the case may be. In the latter case an explosive mixture is formed in the stack and connecting flues, entailing constant risk of destructive explosions.

40 Briefly, my invention consists in a means for cutting off the air supply to the gas producer of a furnace of the type mentioned immediately after the insertion of the charge of raw coal, and gradually turning 45 on the air supply again as the distillation of gas from the raw coal falls off—the air being turned on at such a rate that the quantity of combustible supplied to the furnace is maintained, as nearly as may be, 50 constant.

While I do not limit myself to the use of my invention in connection with any particular type of furnace, I have shown it, in the accompanying drawings, applied to the 55 gas producer of a gas bench, which is oper-

ated on a draft current of mixed air and flue gases.

It is to be understood that my invention is not limited to the specific embodiment shown, but may be used in connection with any type of gas producer whether operated on forced or induced draft. In the latter case the valve member of the apparatus may be a simple gate or vane.

In the drawings, Figure 1 represents the front elevation of a gas bench with my invention applied thereto, the regulating cylinder of the valve being shown in vertical cross section. Fig. 2 is a vertical longitudinal section through the gas bench to the producer of which my invention is applied.

1, is the gas producing chamber of the producer, 2 the air injector, 3 the air regulating valve, 4 the main air line, 4' the air connection from 4 to the nozzle of injector 2, 5 the retort oven of the gas bench with retorts 6 set therein, 7 is the charging chute of the gas producer 1.

The method of operating the apparatus is as follows:—A bed of ignited fuel having been built up in the gas producer in the manner well known to those skilled in the art, the air for supporting combustion in the gas producer enters through the nozzle 8, inducing a draft of combustion gases through the flues 9, which are connected to the flues through which the combustion gases are withdrawn from the retort oven. The mixed draft current of air and products of combustion discharge through the injector 10, under the grate 11 of the producer. Passing up through the fuel on grate 11 the oxygen and CO_2 of the draft current react with the carbon of the fuel thus,

forming producer gas. This passes through the gas nostrils 12, into the retort oven of the gas bench and is burned by air admitted through the air nostrils 13. The hot products of combustion sweep around the retorts and discharge from the oven through suitable off-take flues, to which the flues 9 are connected. On the air-pipe 4' is located the air regulating valve 3. This is simply an ordinary throttle valve 3' on whose stem 26 is mounted a regulating cylinder 19, having a piston 14, and an operating lever 16. The

lever 16 is fulcrumed in a movable link 17 whose other extremity is anchored, as shown, and it has a grip 18 at its free end. The arm of 16 is preferably divided in the same manner as the arm of an ordinary beam scale. A weight 15, is mounted on 16 so as to be capable of adjustment in position longitudinally of 16. The cylinder 19 is preferably supported in rigid connection with the valve 3'. A pipe 20 connects the two ends of the cylinder and has a check valve 21 interposed in it. This valve permits of an unobstructed flow of liquid from the upper side of piston 14 to the lower side but prevents flow in the reverse direction. A pipe 22 of small bore likewise connects the two ends of the cylinder and has interposed in it a needle-valve 23. This valve 23 is capable of fine adjustment so that only a very small stream of liquid can flow from the lower to the upper side of the piston while the flow through 20, as explained above, is free and permits of a rapid transfer of liquid from the upper to the lower side of the piston. It will be seen that by raising the lever 16 the valve stem 26 is moved upward, closing the valve 3'. When 16 is released the action of the weight tends to depress the lever 16, carrying the piston 14 downward and again opening the valve 3'. This motion of 14 is opposed by the liquid (preferably oil) in the cylinder 19 which can only pass from the lower to the upper side of the piston through the small pipe 22 and needle-valve 23. By adjusting the valve 23 and the position of the weight 15 on the arm 16 the free area of the passage and the pressure producing flow may both be varied. Thus the time required for the valve 3' to again open to its full extent may be varied to suit the requirements of each particular case.

The method of applying my invention is as follows:—At intervals, coal is charged through the charging chute 7 onto the fuel bed in the producer. As the coal heats from contact with the hot fuel, its volatile matter is subjected to destructive distillation with the formation of coal gas in the well known manner. Since the theoretical proportion of air required for the combustion of 1 cu. ft. of coal gas is about 6 cu. ft., while for the combustion of the producer gas only 1.12 cu. ft. of air are theoretically required, it is easily seen that, in the customary method of operating the producer, a large quantity of combustible gas will pass unburned through the furnace (or retort oven in this case) unless the proportion of air supplied to the retort oven through 13 is largely increased. This cannot be conveniently done, and would, at any rate, introduce great irregularity into the operation of the gas bench if carried out. By my method of conducting the combustion, immediately before or after charging the raw coal the operator raises the

lever 16, thus, as above explained, displacing the oil in 19 from the upper to the lower side of the piston 14 and closing valve 3'. The closing of 3' momentarily cuts off the air supply to the producer. The quantity of air discharging into the retort oven through the nostrils 13, however, remains fairly constant since this is regulated simply by the draft of the bench and the air dampers. The combustible gas passing through the gas nostrils 12 is, at this point, almost exclusively coal gas, which is distilled off from the raw coal. Under the pressure exerted by the weight, however, the valve 3' immediately after closing, begins to gradually open again, the oil flowing slowly through the valve 22 from the lower to the upper side of the piston. Air is thus again supplied to the producer and the make of producer gas temporarily interrupted is thus again started and gradually increased as the opening of valve 3' supplies more and more air to the fuel bed of the producer. The distillation of gas from the raw coal is at first rapid, the gas being very rich. As the distillation proceeds, both the quantity and quality of the distilled gas falls off. The gradual increase in the air supply, during this period, increases the make of producer gas at a rate that should be adjusted (by the position of weight 15 and adjustment of needle-valve 22) to correspond with and compensate for the diminution in the production of coal gas, thus maintaining a fairly uniform supply of combustible to the retort furnace. Instead of completely closing valve 3', by adjusting the collar 28, which is fastened in any position on 26 by set-screw 29, the degree to which the valve 3' is shut may be regulated to any desired extent. This method of operating may be advantageous where the charges are made at frequent intervals, but are small in quantity.

Having described my invention, what I claim is:—

1. In combination, a gas-producer, a conduit for conducting to said gas-producer the air required to support the combustion therein, a regulating valve on said air conduit, said regulating valve comprising a valve member proper and a regulating member, the said regulating member comprising a cylinder having a piston therein, said piston being rigidly mounted upon the valve stem of said valve member, a pipe connection connecting the two ends of said cylinder, a check valve on said connection, said check valve being adapted to permit a flow of liquid in but one direction through said connection, a second connection connecting the two ends of said cylinder, and an adjustable valve on said second connection.

2. In combination, a gas-producer, a conduit for conducting to said gas-producer the air required to support the combustion there-

in, a regulating valve on said air conduit, said regulating valve comprising a valve member proper and a regulating member, the said regulating member comprising a cylinder having a piston therein, said piston being rigidly mounted upon the valve stem of said valve member, a pipe connection connecting the two ends of said cylinder, a check-valve on said connection, said check-valve being adapted to permit a flow of liquid in but one direction through said connection, a second connection connecting the two ends of said cylinder, an adjustable valve on said second connection for regulating the flow of liquid therethrough, and an operating lever for communicating motion to the valve stem of said valve member.

3. In combination, a gas-producer, a conduit for conducting to said gas-producer the air required to support the combustion therein, a regulating valve on said air conduit, said regulating valve comprising a valve member proper, and a regulating member, the said regulating member comprising a cylinder having a piston therein, said piston being rigidly mounted upon the valve stem of said valve member, a passage connecting the two ends of said cylinder and adapted to permit the flow of liquid from one side to the other of said piston, a check-valve on said passage, a second passage connecting the two ends of said cylinder, an adjustable valve on said second passage for regulating the flow of liquid therethrough, an operating lever attached to the valve stem of said valve member for communicating a motion in one direction to said valve-stem and a weight for communicating a motion in the reverse direction to said valve stem.

4. In combination, a gas-producer, a conduit for conducting to said gas-producer the air required to support the combustion therein, a regulating valve on said air conduit, said regulating valve comprising a valve member proper and a regulating member, the said regulating member comprising a cylinder having a piston therein, the said cylinder being adapted to contain a liquid and the said piston being rigidly mounted on

the valve-stem of said valve member, a passage connecting the two ends of said cylinder and adapted to permit the flow of liquid from one side to the other of said piston, a check-valve on said passage, a second passage connecting the two ends of said cylinder, an adjustable valve on said second passage for regulating the flow of liquid therethrough, an operating lever, adapted to communicate motion to said valve-stem, one extremity of said lever being fulcrumed in a movable link, a weight attached to said lever and capable of adjustment longitudinally of said lever, said lever being attached to said valve-stem at a point intermediate of the length of said lever, whereby a motion in one direction may be communicated to said valve-stem by moving the said lever by hand and a motion in the opposite direction by the movement of said lever under the action of said weight.

5. In combination, a gas producer, a passage for conducting to said gas producer the air required to support combustion therein, a valve on said air passage, means for actuating and regulating said valve, said actuating and regulating means comprising a chamber having a piston therein, a piston rod rigidly attached to said piston, a passage connecting the two extremities of said chamber, a check valve on said passage permitting the flow of liquid in but one direction through said passage from one side of said piston to the other side of the same upon displacement by said piston, means for slowly conducting said liquid back in the reverse direction to the part of said chamber that it first occupied, whereby a slow motion is communicated to said piston, and means for transmitting the motion of said piston to said valve.

Signed at New York city in the county of New York and State of New York this 12th day of February, A. D. 1910.
